UNITED STATES PATENT OFFICE.

WILHELM SEHLBACH, OF BARMEN, GERMANY.

DYEING-MACHINE.

1,162,259.

Specification of Letters Patent. Patented Nov. 30, 1915.

Application filed June 10, 1913. Serial No. 772,808.

To all whom it may concern:

Be it known that I, WILHELM SEHLBACH, of Bredderstrasse 38^a, Barmen, Rhenish Prussia, Germany, have invented new and useful Improvements in Dyeing-Machines, of which the following is a specification.

My invention relates to dyeing apparatus and more particularly to apparatus for dyeing skeins of yarn or other similar material, and according to my invention, I provide tanks for containing dye, a yarn frame supported in each tank, the frames being arranged to reciprocate in the tanks so that the material or yarn supported by the frames, is thoroughly and equally dyed.

In describing the invention in detail reference is had to the accompanying drawing, forming a part of this specification, and which illustrates in Figure 1 a sectional elevation of the apparatus; Fig. 2 is an enlarged section of the tank with its casing or frame. Fig. 3 is a section taken at a right angle to Fig. 2.

Referring to the drawing by reference numeral *a* is denoted an open vat or tank of preferably rectangular shape, which may be closed by a lid of any construction not shown in the drawing.

b is a casing which closely fits the tank and may be guided therein in any suitable manner, said casing consists of a framework in which rods *d* are adjustably arranged on the top and bottom bars *c* as will be seen by the drawings. Said rods *d* are positioned in the slots of the members *c* so that the rods *d* may be easily removed. The rods *f* are connected to the casing by means of hinges *f'*, which permit the rods *f* to be swung upwardly and out of engagement with the bars *c*, whereby the rods *d* may be removed. On said rods *d* the skeins of yarns are suspended and it will be clear that the rods may be adjusted in such a manner that the skeins wholly fill the casing and are supported at an angle with relation to the fluid level in the tanks. The height of the tank is such that the stroke of the frame will be regulated with relation to the tank and that the yarn is not lifted over the level

of the liquor, but is constantly covered by 50 the same. The casing or frame being thus wholly filled with yarn and fitting closely in the tank acts as a plunger, the yarn will be forced therefore through the liquor and all particles of the yarn are saturated with 55 the liquor, which penetrates the same with great vigor so that the dyeing process is carried out in a cheap and yet effective manner. The means for raising and lowering the plunger may be of any suitable 60 construction. In Fig. 1 I have combined two tanks each having a plunger the rods of which are coupled to a rocking beam *e* in order to give to the plunger the necessary motion in an economical way. 65

From the drawing it will be seen that the side rods *b* forming a part of the frame are provided with longitudinal dove tailed recesses forming guides for correspondingly shaped rods *c*, which are notched to receive 70 the skein rods *d*. The rods *c* being relatively shorter than the supporting rods *b*, may be moved longitudinally of the rods *b* and thereby the upper and lower ends of the skeins may be adjusted with relation to 75 each other to change the angle of the skeins with relation to the fluid level of the tanks.

What I desire to secure by Letters Patent is:—

1. In a yarn dyeing apparatus, a tank, a 80 frame in the tank, said frame comprising side and end bars, each of the side bars having a groove, rods having notched portions, the rods having a portion slidably in the grooves, yarn supporting rods held in the 85 notched portions of the bars, a movable member for engaging the rods for holding the same in the notches, and means for moving the frame in the tank.

2. In a yarn dyeing apparatus, a tank, a 90 frame in the tank, said frame comprising side and end bars, each of the side bars having a groove in the inner face thereof, notched bars movable in the grooves, skein supporting rods in the notches of the 95 notched bar, and means for holding the skein supporting rods in the notches substantially as described.

3. In a yarn dyeing apparatus, a tank, a frame in the tank, side bars forming a part of the frame, each of said side bars having a groove, a rod having notched portions positioned in each of the grooves, said rods being shorter than the side bars, which support the same whereby the rods may be

moved longitudinally of the side bars, yarn supporting rods held in the notches, and means for securing the rods in the notches.

WILHELM SEHLBACH. [L.S.]
